UNITED STATES PATENT OFFICE.

VICTOR M. SUMMA, OF ST. LOUIS, MISSOURI, ASSIGNOR, BY MESNE ASSIGNMENTS, TO AMERICAN CAR AND FOUNDRY COMPANY, OF ST. LOUIS, MISSOURI, A CORPORATION OF NEW JERSEY.

CAR STRUCTURE.

1,029,091.

Specification of Letters Patent. Patented June 11, 1912.

Application filed July 19, 1910. Serial No. 572,773.

To all whom it may concern:

Be it known that I, VICTOR M. SUMMA, residing at St. Louis, Missouri, and being a citizen of the United States, have invented certain new and useful Improvements in Car Structures, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a view in side elevation of a side of a car embodying the features of the present invention, a fragment of one end being broken away. Fig. 2 is a longitudinal section therethrough taken approximately on the plane indicated by line 2--2 of Fig. 1 and looking down-wardly. Fig. 3 is a vertical section taken on the plane indicated by line 3--3 of Fig. 1. Fig. 4 is an enlarged detail horizontal section taken on the plane indicated by line 4--4 of Fig. 1.

The object of the present invention is the production of a car of minimum cost and of minimum dead weight and of maximum strength, and said object is attained by the provision of a thin envelop of steel plates reinforced along the lines of forces acting on them by members of appropriate strength proportionate to the stresses to be borne.

In the construction of the car, the forces, as well as their intensity and direction, are determined and the stress members are disposed accordingly and vary in size and capacity proportionately to the respective part of the load to be borne.

Referring to the illustrated embodiment in the accompanying drawing, in which the side of the car or side girder constitutes the side sill, 1 indicates the lower chord, and 3 the upper chord of the truss comprising said girder. Chord 1 is the side connecting member of the cross members of the underframe, while chord 2 is the side plate of the car, and to these chords are fixed the steel plates 3--3 forming the envelop or sheathing of the car. Tension members 4, 5, and 6 are spaced along the side of the car

and connect the upper and lower chords, and a corner angle post tension member 7 connects the respective ends of said chords. Member 4 may, as illustrated, be a relatively wide, flat plate fixed to the steel sheathing of the car along the line of the meeting edges of two plates of such sheathing, and said member may if desired be flanged or otherwise stiffened against buckling. Member 5 is the same in form and arrangement except that it is narrower or otherwise formed of less capacity than tension member 4 to a degree proportionate to the difference in stress to be borne by member 5. Member 6 may be the same in form as 4 and 5 but reduced in size or otherwise reduced in capacity proportionately to the reduction in stress to which it is subjected, but, preferably, for convenience, member 6 is provided with an inturned flange 6' for forming a door post for the side door of the car. The bolster 8 or point of support adjacent the respective end of the car is spaced outwardly from the tension member 4, and a diagonal compression member 9 engages the chord 2 adjacent the upper end of tension member 4 and chord 1 immediately above or adjacent the point of support 8, the compression member 9 being of maximum strength, and a similarly disposed diagonal compression member 10 engages the chord 2 adjacent the upper end of tension member 5 and engages the chord 1 adjacent the lower end of tension member 4, the compression member 10 being diminished in capacity with respect to compression member 9 proportionately to the diminution in the degree of stress. A similarly disposed diagonal compression member 11 engages the chord 2 adjacent the upper end of tension member 6 and engages with the chord 1 at the lower end of tension member 5, and compression member 11 is diminished in capacity proportionately to the diminution in the strength required for carrying the reduced proportionate amount of load with respect to compression member 10. In computing the stresses carried by the several stress members, it is found that a substantially neutral zone exists from the chord 1 to the chord 2 in a vertical line above the point of support, and hence it is unnecessary to provide a stress member along this line. For convenience of construction and for adding to the rigidity of the steel sheathing, the ter-

5 minal plate 3 may be caused to lap the next plate 3, as at 3', along said neutral zone. A diagonal compression member 12 extends from the respective end of the chord 2 adjacent 10 the upper end of tension member 7 to the chord 1 immediately above or adjacent the point of support, that is at the lower end of compression member 9, and said compression members may have their lower ends extending 15 into a pocket 13. The other compression members may likewise be provided with pockets if desired, or all pockets may be omitted, as found preferable.

Compression member 12 is proportioned 20 in size and strength relative to the stress to be sustained, and is therefore of less cross sectional area and strength than compression member 11 in a degree proportionate to the amount of load sustained relative to the load carried by member 11.

Each of the stress members 9, 10, 11 and 12, preferably comprises a Z section with one of its flanges riveted to the respective plate 3 along the length of the Z section, 25 and each of the tension members 4, 5, 6, and 7, is preferably riveted to the plates 3 throughout the length of the respective tension member so that said plates form a unitary part of the truss comprised of the lower and upper chords and the connecting members mentioned, and certain areas of said plates will be in tension and others in compression relative to their position with respect to the tension and compression elements above mentioned. The lower chord or side connecting member 1 is preferably a channel, and the upper chord or plate 2 is preferably a Z section, and each of the tension members 4, 5, 6, and 7, is riveted to the webs of the said chords, and each of the compression members 9, 10, 11 and 12, has its upper end abutting against the under surface of the lower flange of member 2 and its lower end resting upon the upper flange of member 1 or the ends of said compression members may extend into pockets engaging the respective flanges. In order to prevent buckling of the steel sheathing of the car, stiffening angles 14-14 may be provided and preferably extend from member 2 to member 1 along andlapping the meeting edges of the respective plates 3 and riveted to said plates.

I am of course aware that it has been heretofore proposed to vary the size of wood compression members in car structures, for instance as seen in the patent of King, No. 669,797, dated March 12th, 1901, but no attempt has apparently been made in steel car structures to provide a uniform variation in capacity of both tension and compression members relative to the proportionate amount of load to be sustained by each.

It will be noted that the plates 4, 5 and 6, 65 arranged at the lines of the meeting edges

of the sheathing plates 3, serve not only as splice plates for connecting the abutting edges of the sheathing plates, and as tie plates for connecting the upper and lower chords of the girder, but they serve also as gusset plates for connecting the diagonal members to the top and bottom chords of the girder. Plates 3 serve also in the same capacity.

What I claim is:

1. In a car structure, upper and lower chords, tension members extending between and engaging the chords, and compression members extending between and engaging the chords, said tension members being of variant stress sustaining capacities proportionate to the variant stresses to be sustained and comprising gusset plates adapted for connecting said compression members to said girders.

2. In a car structure, upper and lower chords, tension members extending between and engaging the chords and of variant capacities proportionate to the stress occurring at the relative position of the respective tension member, and compression members extending between said chords and of similarly variant capacities said tension members serving as means for connecting said compression members to said chords.

3. In a car structure, upper and lower chords, vertical and diagonal stress members engaging said chords, the diagonal stress members extending each from the upper end portion of one vertical stress member to the lower end portion of the next vertical stress member said stress members being of variant capacities each relative to the proportionate amount of load to be sustained and said vertical stress members being adapted to connect said diagonal stress members to said chords.

4. In a car structure, upper and lower chords, sheathing comprising plates connecting said chords and arranged edge to edge, tension members, each having a relatively flat face lying flat against said plates along the respective meeting edges thereof and fixed thereto, and diagonal compression members, each extending from the upper end portion of one tension member to the lower end portion of the next adjacent tension member and fixed to the sheathing, said tension and compression members being of variant capacities, each proportionate to the relative amount of load to be sustained and said tension members being adapted to connect said compression members to said chords.

5. In a car structure, upper and lower chords, stress sustaining members disposed between said chords, sheathing plates, and splice plates for connecting said sheathing plates, said splice plates and said sheathing plates being adapted for connecting said stress sustaining members to said chords.

6. A car structure comprising upper and lower chords a plurality of alined sheathing plates arranged with juxtaposed edges, a plurality of splice plates adapted to connect said edges, and a reinforcing member connected to one of said chords by one of said splice plates and to the other of said chords by another of said splice plates. 5
7. A car structure, comprising upper and lower chords, a plurality of alined sheathing plates arranged with juxtaposed edges, a plurality of splice plates adapted to connect said edges, and a reinforcing member connected to one of said chords by one end of 10 one of said splice plates and to the other of said chords by a relatively opposite end of another of said splice plates. 15
8. A car structure, comprising upper and lower chords, a plurality of alined sheathing plates arranged with juxtaposed edges, a member fixed to the inner sides of said juxtaposed edges adapted for connecting said edges, a member fixed to the outer side of said juxtaposed edges adapted for connecting 20 said edges, and a reinforcing member extending from one of said chords to the other, one of said plate connecting members being adapted to connect said reinforcing member to one of said chords. 25
9. A car structure, comprising upper and lower chords, a plurality of alined sheathing plates arranged with juxtaposed edges, a splice plate adapted to connect said edges, and a reinforcing member connected to one 30 of said chords by one end of said splice plate and another reinforcing member connected to the other of said chords by the opposite end of said splice plate. 35
10. A car structure, comprising upper and lower chords, a plurality of alined sheathing plates arranged with juxtaposed edges, a member fixed to the inner sides of said juxtaposed edges adapted for connecting said edges, a member fixed to the outer sides 40 of said juxtaposed edges adapted for connecting said edges, and a reinforcing member extending from one of said chords to the other, said outer plate connecting member being adapted to connect said reinforcing member to one of said chords. 45
11. A car structure, comprising upper and lower chords, a plurality of alined sheathing plates arranged with juxtaposed edges, members fixed to the inner sides of said juxtaposed edges adapted for connecting said edges, members fixed to the outer sides of said juxtaposed edges adapted for connecting said edges, and a reinforcing member extending from one of said chords to the other, one of said plate connecting members being adapted to connect said reinforcing 50 member to the other of said chords. 55
12. A car structure, comprising upper and lower chords, a plurality of alined sheathing plates arranged with juxtaposed edges, members fixed to the inner sides of said juxtaposed edges adapted for connecting said edges, members fixed to the outer sides of said juxtaposed edges adapted for connecting said edges and a reinforcing member extending from one of said chords to the other, one of said outer plate connecting members being adapted to connect said reinforcing member to one of said chords and another of said plate connecting members being adapted to connect said reinforcing member to the other of said chords. 60
13. A car structure, comprising upper and lower chords, a plurality of alined sheathing plates arranged with juxtaposed edges, members fixed to the inner sides of said juxtaposed edges adapted for connecting said edges, members fixed to the outer sides of said juxtaposed edges adapted for connecting said edges, and a reinforcing member extending from one of said chords to the other, one of said outer plate connecting members being adapted to connect said reinforcing member to one of said chords and another of said outer plate connecting members being adapted to connect said reinforcing member to the other of said chords. 65
14. A car structure, comprising upper and lower chords, a plurality of alined sheathing plates arranged with juxtaposed edges, and a plurality of splice plates adapted to connect said edges, said splice plates serving as stress sustaining members and each of said splice plates being of a different stress sustaining capacity proportionate to the variant stresses to be sustained. 70
15. A car structure, comprising upper and lower chords, a plurality of alined sheathing plates arranged with juxtaposed edges, a plurality of splice plates adapted to connect said edges, a plurality of stress sustaining members intermediate said splice plates, said splice plates serving as stress sustaining members and each of said splice plates being of a different stress sustaining capacity proportionate to the variant stresses to be sustained. 75
16. A car structure, comprising upper and lower chords, a plurality of alined sheathing plates arranged with juxtaposed edges, a plurality of splice plates adapted to connect said edges, and a plurality of stress sustaining members intermediate said splice plates, said splice plates serving as stress sustaining members and all of said stress sustaining members being of different stress sustaining capacities proportionate to the variant 80 stresses to be sustained. 85
17. In a car structure, the combination of a side connecting member, a side plate, a metallic sheathing connecting said plate and side connecting member and comprising 90

plating disposed edge to edge, tension members formed of band to be carried, and a stiffening member being the side plate and connecting member and connected to the sheathing plates along the lines of the meeting edges of the plates thereof, the meeting edges thereof being only fixed to the sheathing plates along the lines of the meeting edges thereof. In witness whereof I have hereunto set my hand in the presence of two witnesses, 15
5 plates thereof, compression members fixed to said sheathing plates and extending diagonally across the same from the side plate to the side connecting member, the tension and compression members being of various sizes, 10 plates each relative to the proportionate

VICTOR M. SUMMA.
